UNITED STATES PATENT OFFICE

EDWARD H. REMDE, OF CLEVELAND, OHIO, ASSIGNOR TO THE BAKER-RAULANG COMPANY, OF CLEVELAND, OHIO, A CORPORATION OF OHIO

LOAD-HANDLING MECHANISM

Application filed December 19, 1924. Serial No. 757,029.

This invention relates to a load handling mechanism capable of raising or lowering material or bodies, and transporting the material or bodies from one place to another.

5 One object of the invention is to construct a mechanism of this character that is relatively simple in construction and capable of being operated rapidly and economically.

Another object of the invention is to provide 10 a mechanism of this character having improved means for engaging and moving a load in different directions, at will, to insure a rapid raising, transporting and dumping or discharge of the load.

15 Another object of the invention is to construct a mechanism of this character in which a gear reduction is provided between the driven shaft and each winding drum, whereby increased mechanical efficiency and reduction in current consumption and manufacturing costs result.

Another object of the invention is to provide 20 in a mechanism of this character, having a single power unit, for engaging and moving a load in different directions, at will, improved means for controlling the selector means to insure positive operation of the mechanism.

Another object of the invention is to provide 25 in a mechanism of this character an improved gear reduction between the driven shaft and either or both winding drums, the elements of which are arranged to prevent distortion and disalignment of the driven shaft.

A further object of the invention is to improve 30 the construction of load handling mechanism disclosed in my co-pending application filed Dec. 10, 1923, Serial No. 679,605 (see Letters Patent No. 1,777,475, dated October 7, 1930), whereby a relatively high speed motor for operating the winding drums may be used, the batteries operate at their most efficient point of output, less current is consumed in operating the magnetic clutches, and the ratio between the motor shaft and driven shafts for the cable winding drums is increased to drive the latter at a reduced speed.

35 Other objects of the invention will be ap-

parent to those skilled in the art to which my invention relates from the following description taken in connection with the accompanying drawings, wherein

Fig. 1 is a fragmentary front elevation of 55 a load handling mechanism embodying my invention, with the boom supporting frame swiveled or slewed to dispose the boom at one side of the truck frame.

Fig. 2 is a top plan view of the cable operating means.

Fig. 3 is a side view of the parts shown in Fig. 2.

Fig. 4 is a view similar to Fig. 2, but enlarged and having parts broken away to 65 facilitate the illustration.

Fig. 5 is a sectional view on the line 5—5 of Fig. 4.

Fig. 6 is a diagram of the electric circuits for the traction motor, the slewing motor, 70 the motor which drives the operating mechanism, the means which release the drum holding means, and the controllers or switch devices for closing the circuits.

Fig. 7 is a fragmentary plan view of the 75 means which control the operation of the selector means and prevent its movement from one operating position to its other operating position.

Fig. 8 is a fragmentary elevation of the 80 parts shown in Fig. 7.

Fig. 9 is a section on the line 9—9 of Fig. 8.

In the drawings, 1 indicates a frame of any desired shape and form, supported at one end by front wheels 3 and at its other end 85 by rear wheels (not shown).

4 indicates a motor, the shaft of which is connected with the wheels 3 by a suitable power transmitting mechanism enclosed in a housing 4a. 5 indicates a mechanism of any 90 desired construction interposed between the motor 4 and housing members 4a and the frame 1 for connecting them together and permitting relative movements between them. 6 indicates pairs of casing elements enclosing 95 springs 6a between the frame 1 and housing members 4a.

The outer ends of the housing members 4a are preferably shaped to form suitable knuckles 4b on which the traction wheels 3 100

are pivoted for steering purposes. 9 indicates steering connections between the rear wheels and front wheels 3, whereby both pairs of wheels may be simultaneously operated 5 about their pivots for steering purposes.

11 indicates a support for an operative, supported in suitable brackets secured to the lower ends of a pair of uprights 14, secured to the frame 1 and supporting a dash 10 15. The dash 15 preferably supports certain of the controlling or operating elements for the truck and the load supporting and engaging members and the handles or levers for operating these elements. 16 indicates 15 a foot pedal associated with the platform 11, and arranged to control the release and application of a suitable brake mechanism which is normally applied as is customary in apparatus of this character. 20 23 indicates as an entirety a controller for cutting in or closing the circuit to the motor 4, operated by a lever 27 pivoted on the dash 15 to swing in vertical planes. 28 indicates as an entirety a switch mechanism associated 25 with the controller 23 and connected by a linkage 28' with the brake mechanism, so that the operation of the foot pedal will control the switch mechanism to close or open the circuit to the motor 4. 30 29 indicates a post or steering column rotatably mounted in suitable bearings 29a, 29b, and connected to the steering connections 9; a hand lever 32 serving to rotate the column to effect steering of the wheels. 35 33 indicates an axle or pivot member disposed in vertical position on the frame 1 and extending upwardly therefrom to form a vertical shaft for a frame 34, on which the boom 40 is pivoted in a well known manner, the 40 frame 34 being mounted on the shaft 33 at its front end and swingable in either direction, to dispose the boom at one side of the frame, one such position being shown in Fig. 1. Suitable power mechanism (not shown) is 45 provided for swinging or slewing the frame 34, the motor therefor being indicated at 76 in the diagram (Fig. 6).

The motor 76 is controlled by a controller 76a, the drum of which is operated by a link 50 76c connected to a handle 76b, the latter being mounted on the dash 15.

The boom or crane 40 preferably comprises a pair of channel members arranged in spaced relation, connected by a plurality of cross 55 pieces 40b.

The lower ends of the channel bars are mounted on a pivot pin 52. The boom 40 is raised and lowered about the pivot pin 52 by any suitable means, but preferably by means 60 of a cable or other flexible connection 40' connected to an operating means 43, 44 indicates as an entirety operating means for a suitable load engaging member (not shown), suspended by a flexible member 57 from the 65 outer portion of the boom, the flexible member

being operated by the operating means 44 to raise or lower said member.

The load engaging member may be of any desired construction, such as a clam shell bucket or a platform, but preferably comprises a depending hook. 70

The operating means 43, 44, comprises a pair of drums 58, 59, on which the cables 40', 57, respectively, wind and unwind, for swinging the boom 40 about its pivotal support and for raising or lowering the load engaging member. The drums 58, 59, are rotated independently of each other in either direction in the manner to be later set forth, to swing the boom 40 and raise or lower the load engaging member (not shown). The cable 40' may be connected at its inner end to the drum 58 in any desired manner. From the drum 58, the cable 40' leads to and reeves through and around a plurality of sheaves, one being shown at 60, supported by links 65, pivoted on the rod 39b, the opposite or outer end of the cable being suitably anchored. 80

The cable 57 is connected at its inner end in any suitable manner to the drum 59. From the drum 59, the cable 57 runs around a guide sheave 69, supported on a shaft 69a on the outer side of the adjacent upright member 37, and then around a sheave 70 loosely mounted on the pin 52. From the sheave 70 90 95 the cable 57 extends to and around a sheave suitably supported in the free end of the boom 40, and then downwardly, the cable being connected to the load engaging member in any desired manner. 100

102 indicates as an entirety a casting shaped and constructed to form a cradle 102a for the motor 41 and a housing section 102b for the power transmitting mechanism 42. The end walls of the housing section 102b are formed with openings 103 through which the driving means for the drums 58, 59, extend, as will be hereinafter described. The end walls of the housings 103 are thickened to form suitable seats for a pair of annular supporting disks or members 104, and such walls and members are formed with aligned 110 openings to receive cap screws 105 by means of which the disks or members 104 are rigidly secured to the end walls of the housing section 102b. The supporting disks or members 104 are provided with integral extensions to provide feet 106, each of which is secured to an angle 107 carried by the adjacent upright member 38. The feet 106 operate through the disks or members 104 and the housing and cradle casting 102 to support the motor 41 and power transmitting mechanism in fixed relation upon the support 34 and in operative relationship to each other. 115

The motor 41 is fixed to the cradle 102a by a plurality of screws 107'. 108 indicates a housing section clamped to the housing section 102 and enclosing a shaft 109 connected to the motor shaft and a worm 110 which 120 125

meshes with and drives a gear 111 forming one of the elements of the power transmitting mechanism 42.

The power transmitting mechanism 42 for the operating means 43, 44, may be of any desired construction; but I prefer to use some form of gear mechanism, that shown for illustrative purposes comprising a well-known type of differential mechanism, such as is commonly used for driving the wheels of automobiles. By the use of a differential mechanism and of certain devices and means, to be later described, for holding or releasing the driven elements thereof, a single motor may be employed to drive the operating means to rotate either winding drum, at will, in a simple manner. In the illustrated form of construction, the differential mechanism comprises the main gear or worm gear 111, already referred to, connected to a casing 112 and having oppositely extending hubs 113. The hubs 113 are mounted in suitable bearings 114 seated in pillow blocks 115, carried by the housing sections 102b, 108, and secured together in any well known manner. As shown in Fig. 4, the hubs 113 are reduced to form seats for the inner races of the bearings 114. 114a, 114b, indicate ring nuts screw threaded to the pillow blocks 115 and free ends of the hubs, and engaging the races of the bearings to hold them in place. The casing 112 supports a plurality of stud shafts 116, on which loosely rotate bevel pinions 116a. The pinions 116a mesh with bevel gears 117 to drive them. 118 indicates axle sections splined in a well known manner at their inner ends to the hubs of the bevel gears 117. At their outer ends each of the axle sections 118 is connected by a reduction gearing indicated as an entirety at 119, with the adjacent drum 58 or 59 to rotate it in one direction or the other to wind the adjacent cable thereon or permit unwinding therefrom according to the direction of rotation of the motor 41. 121 indicates sleeves surrounding the axle sections 118 and supported at their inner ends in the openings extending through the hubs 104a of the supporting disks or members 104, their flanged inner ends abutting the hubs 104a to prevent their outward movement and their outer ends forming bearings for the drums 58, 59, to rotate on, bushings being mounted on the sleeves to provide suitable bearing surfaces. 123 indicates a dust sleeve loosely fitting each axle section 118, its inner end fitting within the end of the adjacent hub 113 and its opposite end being flanged at 123a and biased by a spring 124 against the inner end of the sleeve 121.

c3 As the reduction gearings 119 between each shaft section 118 and the adjacent drum are similar, it will be necessary to describe but one of them. Of this gearing, 119a indicates a pinion carried by the adjacent shaft section 118 and disposed in a plane beyond the

outer face of the adjacent drum 59—see Fig. 4. The pinion 119a is preferably formed integral with shaft section 118. The shaft section 118 extends beyond the pinion 119a for a purpose which will later appear. 120 indicates a pair of gears rotatably mounted on the outer side of the drum 59, but eccentrically to its axis, the shafts 120a for the gears being preferably arranged in diametrical relation, as shown in Fig. 5. The gears 120 mesh at their inner portions with the pinion 119a and at their outer portions with an internal ring gear 120b which is stationary, being connected to the adjacent disk 104 in the manner to be later set forth, so that when the shaft section 118 is driven the gears 120 are rotated on their axes and also caused to revolve about the axis of the shaft section, thereby rotating the adjacent drum at a speed which is lower than the speed of the shaft section—the ratio in the disclosed construction being substantially eight and one-half to one. The shafts 120a for the planetary gears 120 are mounted in suitable openings 120' formed in thickened walls of the drum web 59'. In the provision of planetary gears, I am enabled to take advantage thereof to maintain the outer end of the adjacent shaft section 118 in line with its axis at all times since the balanced gears 120 prevent any distortion of the shaft section at its outer end.

As will be understood, both drums 58, 59, are operatively connected through the reduction gearings 119, shaft sections 118 and differential mechanism 42 with the motor 41. Accordingly, by locking (by means of a locking or holding means—each indicated as an entirety at 125) one of the driven elements at either side of the differential mechanism 42, the drum associated therewith will be held against movement and the power of the motor 41, when set in operation, will be transmitted through the differential mechanism, the other shaft section and the adjacent reduction gearing 119 to rotate the drum connected to the latter, so that either drum may be rotated as may be desired.

In the illustrated form of construction each locking or holding means 125 is constructed to normally lock the adjacent drum or its driving means, so that both drums are normally held against movement. As a result of this arrangement, I provide and associate with each of the locking means 125 releasing means (indicated as an entirety at 136) either of which may be operated, at will, by a selective mechanism so that either drum may be operated when the motor 41 is driven.

Since the locking and holding means 125 for both drums are similar in construction, it will only be necessary to illustrate and describe one thereof. Each of these means comprises the following instrumentalities: 126 indicates a casing rigidly connected to the disk 104, the latter element serving as one of

the casing members and enclosing the inner face or side of the drum as shown in Fig. 4. The remaining members of the casing consist of a plurality of annular elements 126a, 126b, 5 and 126c and a plate 126d, all rigidly connected, the elements 104 and 126a being preferably secured together by a plurality of cap screws 127 and the elements 126a, 126b, 126c and 126d being preferably secured together by 10 bolts 127a. As shown, the casing element 126b is provided on its inner face with gear teeth (preferably formed integrally therewith) which constitutes the internal ring gear already referred to. By making the casing 15 126 in sections, I provide for ready assembly and disassembly of parts and elements to be later referred to, a well as insure economical manufacture. The casing element 126c is provided on its inner edge with a web or wall 20 128, the purpose of which is to provide one face or disk 129' of a multi-disk brake indicated as an entirety at 129 and an outer wall for the chamber within which the reduction gearing 119 operates, thereby preventing the 25 lubricant for the latter flowing into that part of the casing containing the brake 129. The brake 129 consists of a rotor 129a, preferably in the form of a plate having a hub 129b keyed in any suitable manner to the outer or free end 30 of the shaft adjacent section 118 so as to be rotated thereby, and a plurality of laterally extending pins 129c disposed near the periphery of the plate and uniformly spaced there-around. 130, 131, 132, 133, indicate the 35 remaining brake disks, the disks 130 and 132 having openings to receive the pins 129c on which they are mounted to slide axially of the rotor 129a and to be rotated thereby and the disks 131 and 133 being formed with 40 openings in their peripheries to receive the bolts 127a by means of which they are supported and guided for movement axially of the rotor 129a but held against rotation therewith. As shown, the disks 129', 130, 131, 132 45 and 133 are arranged so that the center disk and outer or end disks are non-rotatively mounted and the remaining disks which rotate with the rotor are disposed between the non-rotative disks to insure maximum frictional engagement between them. The disk 50 133 is preferably in the form of an annular member and formed of soft iron to constitute an armature for a purpose which will later appear. As already set forth, the disks 130, 131, 132 and 133 are slidable or movable in a direction axially of the rotor 129a or shaft section relative to the disk 129' and each other to effect a braking or releasing relation 55 between all the disks. The disks 129', 130, 131, 132 and 133 are preferably normally maintained in braking relation by a plurality of expansion springs 134 mounted in recesses 134a formed in the inner face of the casing element 126d and normally acting against the

annular member 133. By preference friction material 135 is interposed between the disks to provide maximum friction therebetween, this material being preferably secured by rivets to the opposite faces of the disks 130 and 132. The releasing means 136 for releasing the brake and disconnecting each drum therefrom is preferably of the magnetic type, in which event the annular member 133 forms one magnetic element of such means—for example, the armature as already set forth; the other element thereof comprises a winding 136a (preferably of substantially annular shape) fitting a recess 136b, formed in the inner face of the casing element 126d. The winding 136a may be held in the recess 136b by headed bolts 137 mounted in openings 137a formed in the casing member 126d, the heads of the bolts overlapping the winding 136a to hold it in the recess 136b, as well as serving as a spacer between the winding 136a and armature 133 to maintain an air space between them and thus insure the release of the armature 133 from the winding following the de-energizing thereof. 138, 138a, indicate 90 the terminals for the winding 136a connected by leads to the batteries 36 in the manner to be later set forth.

The hub 129b for the rotor 129a is extended laterally in either direction, its inward extending portion fitting in and extending through the opening 128' in web or wall 128 to seal the chamber for the gearing 119, a liquid tight sealing being insured by forming a groove in the inner wall of the opening 128' and a drain 128a leading from the groove back into the gear chamber. The other side of the gear chamber is sealed by a metallic plate 139 of annular form clamped between the casing elements 126a and 126b and engaged by a ring of packing material 140 supported in a groove 58a formed in the side wall of the drum rim. The outer extended portion 129a' of the hub 129b rotatably fits into an opening formed in the casing member 126d, the latter thereby forming a rigid bearing for the outer end of the shaft section 118 and preventing its disalignment while operating, and particularly in the event any of the disks, when in braking relation, assume a non-uniform engagement. As the casing member 126d is rigidly connected through the remaining casing elements to the disk 104 and casting 102, it will be seen that the shaft sections have support at their inner and outer ends.

From the foregoing description it will be noted that each brake 129 is interposed between the adjacent shaft section 118 and the casing 126 and the reduction gearing 119 for the adjacent drum is interposed between the latter and said shaft section, so that the mechanical advantage resulting from the provision of such gearing is effective and obtained in the driving of the drum by the motor 130

41 and in supporting the load which may be the weight of a load engaged by the engaging member or the boom 40, since the weight of the load is transmitted through the drum, 5 gearing 119, shaft section 118, rotor 129a and the rotatable disks to the non-rotatable disks. It will also be noted that by reason of such construction and arrangement, each brake may be relatively small in diameter and comprise but a few disks to sustain the maximum load which the mechanism may be adapted to lift and transport.

It will also be understood from the foregoing description that the disks of both 15 brakes 129 are normally held in braking relation by the springs 134 and operate to lock both shaft sections 118 and both drums 58, 59, against rotative movement, and that either brake may be released by selectively operating 20 the magnetic means 136 by a selective mechanism, to be later described, whereupon the adjacent drum will be operated upon the closing of the circuit to the motor 41. I provide for this selective operation of either 25 drum by a single motor by utilizing a differential mechanism between the motor and drum shafts and taking advantage of the well known principle inherent in such mechanism. By operating the brakes 129 to release 30 the drums by magnetic means 136, I may connect the latter in series with the motor 41 (as will later appear) so that operation of such means will only take place upon closing of the circuit to the motor. This arrangement is 35 preferable for the further reason that it simplifies the construction materially.

The circuits to the coils 136a may be closed by separate switch devices to energize the coils independently and a separate circuit for 40 the motor 41 closed by a suitable controller, may be provided; but for reasons already referred to, as well as to simplify and increase the speed of operation of the load supporting and engaging devices, I prefer to 45 so arrange the circuits for the coils 136a and the switch and control devices therefor, that either coil may be connected in series with the motor, whereby the operation of the controller to drive the motor in either direction will simultaneously effect the operation 50 of either releasing means and the unlocking of the brake acted on thereby to permit operation of the adjacent operating means 43 or 44. As a result either drum 58, 59, may be 55 rotated in one direction or the other to swing the boom 40 about its pivot pin 52 or to raise or lower the load engaging device, as desired. To carry out these operations, I provide (1) a lever 143, pivotally mounted on the dash 60 15 and connected through an arm 144 and link 145 with a crank arm 146, which is connected to the shaft of a controller indicated as an entirety at 147; and (2) a lever 148, pivotally mounted on the dash 15, and connected 65 through an arm 149 and a link 150 with a

crank arm 151 which is connected to the shaft of a switch device 152. The purpose of the controller 147 is to supply current to the motor 41 to drive it in either direction, such operation being dependent upon the movement of the lever 143 to either side of its neutral position, as shown in Fig. 1. The purpose of the switch device 152 is to select or connect either one of the coils 136a, dependent upon which one of the drums is to be operated, in series with the motor 41, so that upon the operation of the controller lever 143, the selected drum will be rotated in one direction or the other, according to the direction of movement of the lever.

The selector lever 148 is shown in a neutral position in Fig. 1, that is, that position in which neither coil 136a is connected in the circuit of the motor and batteries, but by movement of the lever to the right or left, 80 one of the coils may be connected in the circuit as already described. This arrangement insures the complete cutting of current out of one coil and its de-energization before the other coil can be connected to it. The operation of the levers 143 and 148 and the controllers 147, 152, operated thereby, respectively, will be more clearly understood from the diagrammatic view (Fig. 6), which will be later described.

The motor 41 is preferably of the electric type in order that it may be operated from batteries and co-operate with the operation of the means for releasing the drum holding means herein illustrated and described; but 90 it will be understood that the holding means and the motor may be operated in some other manner without departing from the scope of the invention. The motor 41 may be of any desired construction.

As will be understood from the foregoing description, the load is raised and lowered by winding the cable or rope 57 on or unwinding it from the drum 59, the crane 40 is swung upwardly or downwardly by winding the 105 cable or rope 40' on or unwinding it from the drum 58 and the support 34 is swung or rotated about the shaft 33 by the operation of the motor 76. The movement of each of these elements is automatically stopped when moved in either direction (except in the downward movement of the load engaging element) at a predetermined position by a mechanism which opens the circuit to the motor that operates such element. The mechanisms for stopping the movements just referred to may be similar in construction, each being preferably similar in construction to the mechanism which forms the subject matter of my aforesaid copending application Serial No. 679,605. The mechanism for stopping the swinging or rotation of the frame 34, comprises a switch means 163 enclosed in a casing 163'. The casing 163' is fixed to a plate 163a, supported upon the horizontal 110 120 125 130

bars 39. The switch means 163 is provided with an operating arm 163b, with which engages either of a pair of tappets, carried by the shaft 33, accordingly as the frame 34 5 swings in one direction or the other. The tappets are so arranged that when either one thereof strikes or engages the arm 163a, the switch means 163 will open the circuit and effect the stopping of the motor 76 so that the 10 frame will not swing around and engage the dash 15. The mechanism for stopping the movement of the boom is not shown. The mechanism for stopping the raising of the load engaging member or element comprises 15 a switch means 169 enclosed in a casing carried by the boom 40. A flexible connection 170 is connected at one end to the arm 171 of the switch means and leads over the outer end of the boom and suspends a weight (not 20 shown) in the path of the load engaging member, so that when the latter moves upwardly it lifts the weight and permits the switch means to stop the motor 41.

Referring to Fig. 6: the traction motor 4 25 is connected with the terminals of the controller 23 by leads constituting the circuits 176, 176a, to control the direction of rotation of the motor and leads 177, 177a, to the terminals of terminal blocks 178, 178a, and 30 through wires 179, 179a with the opposite sides of the batteries 36. 180 indicate a connection in the circuit leads 179, 179a, which permits the batteries to be connected with the terminals or with a charging plug to 35 recharge the batteries.

The circuit for the motor 76 may be traced as follows: from the terminal 178a by the lead 180' to the terminal 181 of the switch means 163; if the frame 34 is to be rotated to 40 the right, the circuit is through the lead 182 to terminal 183, across contact 184 to terminal 183, lead 186, terminal for brush 187, through an armature to terminal of brush 188, lead 188a, winding of brake solenoid 189, lead 45 189a, terminal 190, across contact 191, to terminal 192, through lead 192a, to terminal 193, through series field 194 and lead 195 to lead 177; by preference to maintain the motor at a selected speed without regard to its load, 50 I provide a shunt field 196 connected at one end to the series field terminal 193 and at its other end through lead 197 to terminal 198 and contact 184.

If the frame 34 is to be rotated to the left, 55 as shown in Fig. 1, the circuit is traced as follows: terminal 178a, lead 180', terminal 181, lead 199, to terminal 199a, contact 200, to terminal 190, lead 189a, winding of brake solenoid 189, lead 188a, terminal 188, through 60 armature to terminal 187, lead 186, terminal 185, contact 201, terminal 192, lead 192a, terminal 193, through series field 194 and lead 195; the shunt circuit being similar as the circuit already described, except that it is 65 connected to the terminal for the other brush.

If the boom 40 is to be raised, the circuit for the motor 41 and the electro-magnet to be connected in series with the motor 41 so as to release the brake 129 which holds the drum 58, is traced as follows: from terminal 178a, 70 through lead 202, terminal 202a, lead 203, winding 136a of magnet 136 adjacent the drum 58, lead 204, terminal 205 of switch means 165, terminal 206, lead 207, contact 208, contact 209, terminal 210 of the selector 75 switch 152, lead 211, terminal 212 of the controller 147, contact 213, terminal 214, lead 215, terminal 216, motor brushes, terminal 217, lead 217a, terminal 218, contact 219, terminal 220, leads 221, 222, field coils 223 and lead 224 80 to terminal 178; if the boom 40 is to be lowered, the circuit is as follows: from terminal 178a, through lead 202, terminal 202a, lead 203, winding 136a of magnet 136, lead 204, terminal 205 of switch means 165, terminal 85 225, lead 226, terminal 227 of the selector switch 152, contact 228, terminal 229, lead 230, terminal 231 of the controller 147, contact 232, terminal 218, lead 217a, terminal 217, motor brushes, terminal 216, lead 215, terminal 214, 90 contact 233, terminal 234, lead 235, lead 222, field coils 223 and lead 224 to terminal 178.

If the load engaging element is to be raised, the circuit may be traced as follows: from the terminal 178a, through lead 202, terminal 95 202a, winding of electro-magnet 136a, adjacent the drum 59, lead 238, terminal 239 of switch means 169, terminal 240, lead 241, terminal 242, contact 243, terminal 210, lead 211, terminal 212, contact 213, terminal 214, 100 lead 215, terminal 216, brushes of motor 41, terminal 217, lead 217a, terminal 218, contact 219, terminal 220, leads 221, 222, field coils 223 of motor and lead 224 to terminal 178. If the load engaging element is to be lowered, the 105 circuit may be traced as follows: from terminal 178a through lead 202, terminal 202a, winding of electro-magnet 136a, leads 238, 244, terminal 245, contact 246, terminal 229, lead 230, terminal 231, contact 232, terminal 110 218, lead 217a, terminal 217, brushes of motor, terminal 216, lead 215, terminal 214, contact 233, terminal 234, lead 235, lead 222, field coils 223 and lead 224 to terminal 178.

247 is a resistance arranged to be connected 115 in shunt with the motor circuit when the motor is operated to lower the boom 40 or the load engaging member, to prevent acceleration in the speed of the motor shaft.

From the foregoing description, it will be 120 seen that I have provided a load handling mechanism in which the load may be moved or operated in any one of a plurality of directions in a rapid and simple manner, for example, by a raising or lowering of the load engaging member, and by a raising or lowering of the boom; such operations being effected by providing a locking means for certain elements through which the power of the motor is transmitted to the driven means and 125 130

causing a release of one of such elements accordingly as one movement of the load or another is desired. While I have shown an electrically operated means for operating—that is, releasing—either brake, it will be understood that other types of release means may be employed.

In my construction I am enabled to effect the various operations of the load engaging member and the boom from a single motor and a unitary driving or power transmitting mechanism, which tends toward economy and simplicity as well as compactness of the construction.

It will also be noted that the selector handle and the controller actuated thereby are arranged to be set at a neutral position, at which time neither electro-magnet winding is energized, and that they must be moved in one direction or the other to effect the operation (release) of the desired braking elements. By this arrangement I insure the de-energizing of one magnet winding prior to the energizing of the other magnet winding, so that proper operations of the load engaging member and boom to handle the load as desired are effected in a rapid and positive manner.

By providing a gear reduction between each shaft section 118 and the adjacent drum, I am enabled to operate the motor 41 and batteries at their maximum points of efficiency, thereby insuring minimum current consumption in operation of the truck and the load handling mechanisms with resulting economy in handling loads and material.

248 indicates as an entirety means for preventing operation of the selector switch from one operating position to the other operating position, when the motor 41 is operating in either direction (see Figs. 7 and 8). While these means prevent abnormal operation of the selector switch while the motor is in operation, and possible damage to the mechanism and surrounding objects, its primary reason is to make it necessary to stop the motor 41 (or at least slow it down) before shifting the selector switch to insure sufficient current in the circuit to operate the magnetic clutch for releasing the other drum. The means 248 are preferably connected with and actuated by the controller lever 143. Of the means 248, 249 indicates a plate preferably loosely pivoted on a stud shaft 249a carried by the dash 15 and carrying at its upper end a laterally projecting flange 249b adapted to be disposed in the path of movement of a portion of the selector switch lever 148 to prevent its movement in either direction from either operating position to the other operating position. In the preferred form of construction I arrange the flange 249b, when in normal position, (see Fig. 8), so that it will be cleared by the head 252 of the bolt, which forms the pivot connection between the lever arm 149 and rod 150, when the arm 149 moves

from one extreme position to the other extreme position (see dotted lines in Fig. 8). The plate 249 is preferably so mounted and constructed that the flange 249b, when in operative position is substantially midway between the extreme operating positions of the selector switch lever 148, this construction necessitating but one flange to prevent movement of the lever from either position to the other and permitting the lever to be moved, at will to substantially its neutral position from either operative position. 250 indicates the connections between the plate 249 and the switch lever 143. The connections 250 preferably comprise a pair of pivotally connected links 250a, 250b, one (250a) being pivotally mounted on the shaft 249a and the other (250b) being pivotally connected to the outer end of the arm 144. The link 250a is rigidly connected—for example, by a rivet—to the plate 249. When the lever 143 is in neutral position, the flange 249b is in its non-operative position (see full lines in Figs. 7 and 8), thereby being disposed out of the path of movement of the bolt head 252. If now the lever 148 is operated to either position and the lever 143 is operated to run the motor 41, movement of the latter lever in either direction will swing the plate 249 to the position shown in dotted lines in Fig. 8, and thus position the flange 249b in the path of movement of the bolt head 252.

To those skilled in the art to which my invention relates many alterations in construction and widely differing embodiments and applications of the invention will suggest themselves without departing from the spirit and scope thereof. The disclosures and the description herein are purely illustrative and are not intended to be in any sense limiting.

What I claim is:

1. In apparatus of the class described, the combination with a frame and a source of electric current supply, of an electric motor arranged to be connected with said source of supply, a differential mechanism connected to and operated by said motor, a plurality of mechanisms for handling and positioning a load, a drive connection between each said handling mechanism and one of the driven elements of said differential mechanism, means between said frame and each of the driven elements of said differential mechanism arranged to normally hold the latter against movement, magnetically operated means for releasing either of said holding means, means for connecting said motor with said source of supply, and means for selectively connecting in series in the circuit between said motor and said source of supply either of said magnetically operating releasing means, whereby the connection of said motor with said source of supply will simultaneously effect the operation of one of said releasing means.

2. In apparatus of the class described, the combination with a frame and a source of electric current supply, of an electric motor arranged to be connected with said source of supply, a differential mechanism having a main gear connected with and driven by said motor, a plurality of operating mechanisms each having gear reduction driving connections with the driven elements of said differential mechanism, holding devices between said frame and each of said driven elements arranged to normally hold the latter against movement, magnetically operated means for releasing either of said holding devices, means for connecting said motor with said source of supply, and means for selectively connecting in series in the circuit between said motor and said source of supply either of said magnetically operating releasing means, whereby the connection of said motor with said source of supply will simultaneously effect the operation of one of said releasing means.

3. In apparatus of the class described, the combination with a frame and a source of electric current supply, of an electric motor arranged to be connected with said source of supply, a differential mechanism having a main gear connected with said motor, a plurality of operating mechanisms each having gear reduction driving connections with the driven elements of said differential mechanism, devices between said frame and each of said driven elements arranged to normally hold the latter against movement, magnetically operated releasing means associated with each of said holding devices, means for connecting said motor with said source of supply to drive it in either direction, and means for selectively connecting in series in the circuit between said motor and said source of supply either of said magnetically operating releasing means irrespective of the direction of rotation of said motor, whereby the connection of said motor with said source of supply will simultaneously effect the operation of one of said releasing means.

4. In apparatus of the class described, the combination of a plurality of mechanisms, a motor and driving means common to said mechanisms for operating them, locking devices normally tending to lock each of said mechanisms against movement, a source of power supply, operating devices for connecting said supply to said motor, means for selectively releasing said locking means, and means for preventing the operation of said releasing means from operative relation with one of said locking means to operative relation with the other locking means except when said operating devices are inoperative position.

5. In apparatus of the class described, the combination of a plurality of mechanisms, a motor and driving means common to said

mechanisms for operating them, locking devices normally tending to lock each of said mechanisms against movement, a source of power supply, operating devices for connecting said supply to said motor, releasing means for selectively releasing said locking means, a lever movable to different positions for operating said releasing means, and means interposed between said operating devices and said lever for preventing operation of the latter from one operative position to its other operative position except when said operating devices are inoperative position. 70 75

6. In apparatus of the class described, the combination of a plurality of mechanisms, a motor and driving means common to said mechanisms for operating them, locking devices normally tending to lock each of said mechanisms against movement, a source of power supply, operating devices for connecting said supply to said motor, means for selectively releasing said locking means, said means including an element movable to different positions, and a member actuated by said operating devices into the path of movement of said element to prevent movement thereof from either operative position to a point beyond its neutral position except when said operating devices are in inoperative position. 80 85 90 95

7. In apparatus of the class described, the combination with a frame and a source of power supply, of a motor and means including an operating device for connecting said motor with said source of power supply, a differential mechanism connected to and operated by said motor, a plurality of mechanisms for handling and positioning a load, a driving connection between each said handling mechanism and one of the driven elements of said differential mechanism, means between said frame and each of the driven elements of said differential mechanism normally operating to hold the latter against movement, a releasing means for each of said holding means, and means for relating either of said releasing means with said connecting means between said motor and source of supply, whereby the operation of said operating device will operate one of said handling mechanisms. 100 105 110 115

8. In apparatus of the class described, the combination with a frame and a source of power supply, of a motor and means including an operating device for connecting said motor with said source of power supply, a differential mechanism connected to and operated by said motor, a plurality of mechanisms for handling and positioning a load, a driving connection between each said handling mechanism and one of the driven elements of said differential mechanism, each said connection including a reduction gearing, means between said frame and each of said 120 125 130

handling mechanisms normally operating to hold the latter against movement, a releasing means for each of said holding means, and means for relating either of said releasing means with said connecting means between said motor and said source of supply, whereby the operation of said operating device will operate one of said mechanisms.

9. In apparatus of the class described, the combination with a frame and a source of power supply, of a motor and means including an operating device for connecting said motor with said source of power supply, a differential mechanism connected to and driven by said motor, a plurality of mechanisms for handling and positioning a load, a driving connection between each said handling mechanism and one of the driven elements of said differential mechanism, means between said frame and each of the driven elements of said differential mechanism normally operating to hold the latter against movement, a releasing means for each of said holding means, and devices for selectively relating either of said releasing means with said connecting means.

10. In apparatus of the class described, the combination with a frame and a source of power supply, of a motor and means including an operating device for connecting said motor with said source of power supply, a differential mechanism connected to and driven by said motor, a plurality of mechanisms for handling and positioning a load, a driving connection between each said handling mechanism and one of the driven elements of said differential mechanism, means between said frame and each of the driven elements of said differential mechanism normally operating to hold the latter against movement, a releasing means for each of said holding means, and devices for selectively relating either of said releasing means with said connecting means, whereby one of said releasing means operates simultaneously with the completing of the connection between said motor and said source of power supply.

11. In apparatus of the class described, the combination with a frame, and a source of electric current supply, of an electric motor arranged to be connected with said source of supply, a differential mechanism connected to and operated by said motor, a plurality of mechanisms for handling and positioning a load, each said mechanism including a drum, a flexible member arranged to wind on and off the drum and a drive connection having a reduction gearing between each said drum and one of the driven elements of said differential mechanism, means between said frame and each of said drums arranged to normally hold the latter against movement, magnetically operated means for releasing either of said holding means, means for connecting said motor with said source of supply to drive

it in either direction, and means for selectively connecting in series in the circuit between said motor and said source of supply either of said magnetically operating releasing means irrespective of the direction of rotation of said motor, whereby the connection of said motor with said source of supply will simultaneously effect the operation of one of said releasing means.

12. In apparatus of the class described, the combination with a frame, of a plurality of operating mechanisms, a source of electric power supply, a motor, a differential mechanism connected to and operated by said motor, the driven elements of said differential mechanism being in driving connection with said mechanisms, respectively, each said driving connection including a reduction gearing, means for connecting said motor with said source of power supply to drive it in either direction, means normally operating to hold the driven element of each of said mechanisms against movement, and means, including a selective device, correlated with said connecting means and arranged to release either of said holding means dependent upon the position of said selective device, upon the operation of said connecting means.

13. In apparatus of the class described, the combination with a frame and a source of electric current supply mounted thereon, of a plurality of operating mechanisms, an electric motor, a differential mechanism connected to and operated by said motor, the driven elements of said differential mechanism having driving connection with said mechanisms, respectively, and arranged to drive them in either direction, each said driving connection including a reduction gearing, means for normally holding each of said mechanisms against movement, means for connecting said motor with said source of supply to drive the motor in either direction, and means for releasing either of said holding means when the connections between said motor and said source of supply are completed, said releasing means comprising a magnet arranged to actuate each holding means and a movable device arranged to alternately connect either magnet in series in said connections, whereby the completion thereof actuates one of said releasing means.

14. In apparatus of the class described, the combination with a frame and a source of power supply, of a motor arranged to be connected with said source of power supply, a plurality of operating mechanisms, a differential mechanism having a main gear connected with and driven by said motor, separate driving connections in driving relation with each of said operating mechanisms, each said driving connection including a reduction gearing, devices between said frame and each of said operating mechanisms for normally

holding the latter against movement, means for connecting said motor with said source of power supply to drive it in either direction, a releasing means associated with each 5 of said holding means, and means for selectively relating either of said releasing means with said connecting means, whereby operation of the latter to drive the motor will operate the selected releasing means and release said holding means.

10 15. In apparatus of the class described, the combination with a frame and a source of electric power supply, of a motor arranged to be connected with said source of power supply, a differential mechanism having a main gear connected with and driven by said motor, a plurality of operating means having driving connections with the driven elements of said mechanism, each said connection including a reduction gearing, devices between said frame and each of said operating means for normally holding the latter against movement, a magnet for releasing each of said holding means, a circuit between said motor 20 and said source of power supply, a pair of levers, one to connect into said circuit either of said magnets and the other to close the said circuit, and connections between said levers arranged to prevent return of said first 25 lever when the other lever is in operated 30 position.

16. In apparatus of the class described, the combination with a frame and a source of power supply, of a motor arranged to be connected with said source of supply, a differential mechanism having a main gear connected to and driven by said motor, means for connecting said motor with said power supply to drive it in either direction, separate 35 operating means having gear reduction driving connections with the driven elements of said mechanism, means normally holding each of said operating means against movement, means arranged to release each of said 40 holding means, and a device interrelated with said connecting means and each of said releasing means and arranged to cause operation of either of the latter means when said motor is 45 set in operation.

50 17. In apparatus of the class described, the combination with a frame and a source of power supply, of a motor arranged to be connected with said source of power supply, a differential mechanism operatively connected 55 with said motor, a plurality of operating mechanisms, a driving connection including a reduction gearing between each operating mechanism and an element driven by said 60 differential mechanism, devices between said frame and each of said operating mechanisms for normally holding the latter against movement, a releasing means associated with each 65 of said holding means, means for connecting said motor to said source of supply, and de-

vices for relating either of said releasing means with said connecting means.

In testimony whereof, I have hereunto subscribed my name.

EDWARD H. REMDE.
